[57] CLAIM

The ornamental design for the inflatable specimen receptacle, as shown and described.

DESCRIPTION

FIG. 1 is a top, front and right side perspective view of an inflatable specimen receptacle showing my new design;

FIG. 2 is a front elevation view thereof;

FIG. 3 is a rear elevation view thereof;

FIG. 4 is a side elevation view thereof; the opposite side being a mirror image; and,

FIG. 5 is a top plan view thereof, the bottom being a mirror image.

FIG. 1

FIG. 2

FIG. 3

FIG. 4

FIG. 5
